ADJUSTABLE RESISTOR

Marlan E. Bourns, Altadena, Calif.

Application February 20, 1948, Serial No. 9,697

7 Claims. (Cl. 201—56)

1

This invention relates to adjustable resistors, and more particularly to adjustable resistors which must respond precisely and without ambiguity to the means which actuates the movable slider.

For many applications, particularly the detection and telemetering of conditions in and around a moving aircraft, it is essential that the detecting element be capable of being positioned accurately, precisely, and without lag in response to the condition to be observed.

It is an object of this invention to provide an adjustable resistor suited to be actuated by a detecting element as described immediately above.

It is another object of this invention to provide an adjustable resistor which will be rugged, reliable, simple in construction, and easily and accurately assembled.

It is another object of this invention to provide an adjustable resistor which may be subjected to accelerations up to 10 G without detrimental effect to the instrument, and without producing a false electric output.

It is another object of this invention to provide an adjustable resistor in which the electrical detection properties are very sensitive to the physical displacement of the mechanical arm and slider.

It is a further object of this invention to provide an adjustable resistor in which the actuating arm and slider may be moved by a very low actuating force.

It is a still further object of this invention to simplify adjustable resistor construction so that the instrument may be partially dismantled for installation and/or transportation and assembled without in the slightest altering the calibration of the instrument.

It is an additional object of this invention to provide an adjustable resistor in which the slider which rides on the adjustable resistor will not disengage from the element when the instrument is subjected to high acceleration and to severe vibration.

Another object of this invention is to simplify adjustable resistor construction so that need for special limit stops in the oscillatory path of the actuating arm is eliminated.

In accordance with these objects and with other objects which will become apparent in the following specification, the instant invention is embodied in a base, in which is movably mounted an actuating member or arm. Resilient contact means in the form of a resilient piece of conducting material is secured to the actuating member. A cover member is mounted on the base. Simplicity of construction is enhanced by fabricating the cover member of non-conducting material, and mounting on the inner face thereof

2

a resistance element and a contact piece, the former engaging (when the cover is in place) a portion of the resilient contact means, the latter engaging another portion of the contact means.

5 Thus, when the cover member is secured in place to the base, the resilient contact means is automatically engaged with the resistance element and with the contact piece at a proper, predetermined contact pressure.

10 Two embodiments of the invention described generally above have been illustrated in the drawings, wherein:

Figs. 1, 2, 3, and 4 illustrate a preferred embodiment, Fig. 1 being a plan view of the adjustable resistor with the cover partially broken away, Fig. 2 being a sectional elevation taken along line 2—2 in Fig. 1, Fig. 3 being a cross section taken along line 3—3 in Fig. 1, and Fig. 4 being a fragmentary section taken along line

20 4—4 in Fig. 2;

Fig. 5 is a diagrammatic sketch of the circuitry involved in the invention; and

15 Figs. 6, 7, 8, and 9 illustrate another embodiment of the instant invention, Fig. 6 being an elevation partly sectioned, Fig. 7 being a cross section taken along line 7—7 in Fig. 6, Fig. 8 being a view looking at the underside of the cover along the line 8—8 in Fig. 6, and Fig. 9 being a perspective view of one of the contact elements

25 30 removed from the instrument.

First embodiment

Referring to Figs. 1, 2, and 3, 11 designates a base having a recess 12 therein, partially closed by a wall 13 secured to the base 11 by screws 14, and accurately positioned by dowel pins 15. Extending through the base 11, the recess 12, and into the wall 13 is a shaft 16 rotatably mounted therein by means of ball bearings 17. Secured

35 to the shaft 16 by any suitable means, such as a diametral pin 18, is an arm 19 made of non-conducting material. The arm 19 is thus oscillatable with respect to the base 11 by means of the shaft 16, the position of which is in turn controlled by a vane 21, having formed on one end

40 thereof a hub 22 bored at 23 to accept the external end of the shaft 16. The seating of a diametral pin 24 protruding from the shaft 16 in a pair of diametrically disposed V notches 26 in

45 the hub 22 assures that the vane 21 will always be assembled in the proper predetermined relation with respect to the arm 19. A screw 27 extending through the end of the hub and threaded into the end of the shaft 16 serves to anchor

50 55 the vane 21 to the shaft 16.

Near the end of the arm 19 opposite the shaft 16 there is secured, by means of screws 28, a resilient contact strip 29 of conducting material. The strip 29 is disposed generally parallel to the arm 19, and the two ends of the strip

60

face outwardly of the recess 12, being terminated by button contact members 31 and 32, respectively.

Both elements with which the contact strip 29 engages are attached to the inner face of a non-conducting cover 33, which, in the final assembly, is secured to the base 11 over the recess 12 by screws 34. One of these elements, a wire wound elongate resistance element 36, is disposed in an arcuate groove 37 formed on the inner face of the cover 33, and held thereto by means of terminal members 38, which extend through and are secured to the cover 33. The arcuate disposition of the groove 37 is adjacent the oscillatory path of the end 32 of the resilient strip 29, so that the strip 29 is constantly in contact with some portion of the resistance element 36 during all times that the cover 33 is in place. The element 36 is connected, both mechanically and electrically, at each end to the respective terminals 38, by means of metallic strips 39, which are attached to the inner ends of the terminals 38 by the peening of the latter at 41, and hooked over the element 36 at each end thereof as shown at 42. The members 38 and 39 thus serve the double function of securing the element 36 to the inner face of the cover 33, and of providing electrical connections to each end thereof. The terminal members 38 are drilled and tapped externally of the cover 33 to accommodate terminal screws 43, to which may be connected lead wires for the resistor.

The contact member 31 on the other end of the resilient strip 29 is in constant contact with a conducting piece or plate 44 held to the inner face of the cover 33 by a terminal member 46 passing through and secured in the cover 33. Like the terminal member 38, the member 46, which is peened over the surface of the plate 44 at 47, serves the double function of physically holding the plate 44 in place and of providing an electrical connection to the plate. The members 46 and 38 are splined, as exemplified at 48, to prevent turning. Member 46 is drilled and tapped externally of the cover 33 to accommodate a terminal screw 49. A small screw 50 passing thru the plate 44 into the cover 33 prevents the plate from turning about the terminal member 46.

To minimize the effect of extraneous acceleration on the instrument and to further enhance its response characteristics, a counter-balance screw 51 is threaded into the arm 19 paralleling the strip 29. Screw 51 has a knurled head 52 to aid in the balancing of the instrument while the arm 19 is mounted to the base 11. A transverse set screw 53 threaded into the arm 19 serves to anchor the counter-balance screw 51 in place after adjustment.

Gross-balancing is effected by means of a screw 54 mounted in a tapped bore extending transversely through the arm 19 at a right angle to the shaft 16. After adjustment, the screw 54, which is generally positioned fully within its bore, is anchored in place by a set screw 56.

Low density material is employed for the vane 21 to lower inertia, thereby reducing lag in response, and minimizing the undesirable effects of acceleration. The instrument is of manifest simplicity, being directly actuated without the employment of gears, links, or similar mechanisms. The frictional torque which the vane 21 must overcome is minimized by pivoting the shaft 16 in the ball bearings 17, by using low contact pressure at button contacts 31 and 32, and by disposing the contact 31 as near as feasible to the

shaft 16, thereby minimizing the moment arm. The non-conducting cover member 33 serves the triple function of a cover, an insulator between elements, and means for securing the elements in position.

5 A vane actuated resistor constructed in accordance with the above description has been found to be rugged, reliable, precise, and to be electrically sensitive to an angular displacement of three minutes of arc on the part of the shaft 16.

Second embodiment

In the embodiment shown in Figs. 6, 7, 8, and 9, 15 61 represents a base having a groove therein formed of two portions, a bore 62 and a slot 63 communicating with the top of the base 61. A shaft 64 is reciprocably mounted in the bore 62, being prevented from rotation therein by a post 66 extending radially from the shaft 64 and through the groove 63 to a region above the base 61. A contact plate 67 is secured to the top of the post 66 at a right angle thereto by a screw 68, and is insulated therefrom by a fiber washer assembly 70. Each side of the plate is slotted and the resulting strips are bent upwardly to form resilient contacts 69 and 71.

30 A cover 72 made of non-conducting material is secured to the base 61 over the groove 63, and carries an elongate resistance element 73 and an elongate conducting strip 74 seated in grooves 76 and 77, respectively, formed in the inner face of the cover 72. The element 73 is held in place by being secured at each end, as by soldering, to a pair of strips 81, the opposite ends of the strips 81 being held to the inner face of the cover 72 by the terminals 82 which are peened over the strips 81 at 83. In a similar manner, the elongate strip 74 is held to the cover 72 by the strip 84 and the terminal 86.

35 Each of the terminals 82 and 86 is drilled and tapped for reception of terminal screws 87.

The end of the base 61 opposite the mouth of the bore 62 is provided with a boss 88 through which extends a threaded mounting stud 89, by 40 means of which the adjustable resistor may be pivotally mounted to follow swinging movement of whatever driving means may be actuating shaft 64.

45 It will be noted that the groove 63 terminates short of the ends of the base 61, so that the post 66 abutting the ends of the groove 63 limits reciprocation of the shaft 64. Screws 91 serve to secure the cover 72 to the base 61.

50 Like the first embodiment, shown in Figs. 1, 2 and 3, the embodiment just described is also rugged, reliable, and simple in construction. Like the first embodiment also the insulating cover member carries all the electrical terminals, yet is completely free of the actuating element, i. e., the shaft 64. Thus, the final assembly step, which is the simple placing of the cover 72 upon the base 61, automatically effectuates engagement between the two pairs of contact elements at a predetermined proper contact pressure.

55 An adjustable resistor constructed as described above has been found to be able to electrically detect a movement as small as 0.002 of an inch of the part of the shaft 64.

60 What is claimed is:

65 1. An adjustable resistor comprising a recessed base, a wall partially closing the recess in said base, a shaft rotatably mounted in said base and said wall and spanning said recess therebetween, a control arm secured to said shaft between said wall and said base and oscillatable thereby with

respect to said base, a contact strip secured intermediate its ends to said arm, a cover member secured to said base, an arcuate resistance element mounted to the inner face of said cover member adjacent the path of movement of one end of said strip, an edge of said element pressing against said one end, and a contact plate secured to the inner face of said cover member adjacent the path of oscillation of the other end of said strip.

2. An adjustable resistor comprising a base, a shaft rotatably mounted in said base, a control arm secured to said shaft and oscillatable thereby with respect to said base, a wind vane secured to said shaft opposite said arm externally of said base effective to control position of said arm, a counter balance adjusting screw threaded into said arm opposite said shaft, a contact strip secured intermediate its ends to said arm, a cover member secured to said base, an arcuate resistance element mounted to the inner face of said cover member adjacent the path of movement of one end of said strip, an edge of said element pressing against said one end, and a contact plate, secured to the inner face of said cover member adjacent the path of oscillation of the other end of said strip.

3. An adjustable resistor comprising a base, a shaft rotatably mounted in said base, a control arm secured to said shaft and oscillatable thereby with respect to said base, a contact strip disposed generally parallel to said arm and secured intermediate its ends to said arm, a cover member secured to said base, an arcuate resistance element mounted to the inner face of said cover member adjacent the path of movement of the outer end of said strip, an edge of said element pressing against said outer end, a contact plate, a terminal passing through said cover member and securing said plate to the inner face of said cover member adjacent the path of oscillation of the inner end of said strip, and a pair of terminals passing thru said cover member at the respective ends of said element and attached to said element to secure the same to said base.

4. An adjustable resistor comprising a recessed base, a wall partially closing the recess in said base, a shaft rotatably mounted in said base and said wall and spanning said recess therebetween, a control arm secured to said shaft between said wall and said base and oscillatable thereby with respect to said base, a contact strip disposed generally parallel to said arm and secured intermediate its ends to said arm, a cover member secured to said base having an arcuate groove on its inner face adjacent the path of oscillation of the outer end of said strip, an arcuate resistance element mounted in said groove, an edge of said element pressing against said outer end, a contact plate, a terminal passing thru said cover member and securing said plate to the inner face of said cover member and securing said plate to the inner face of said cover member adjacent the path of oscillation of the inner end of said strip, and a pair of terminals passing thru said cover member at the respective ends of said element and attached to said element to secure the same in said groove.

5. An adjustable resistor comprising a recessed base, a shaft rotatably mounted in said base and extending into the recess, a control arm secured to said shaft and oscillatable thereby within said recess, a wind vane secured to said shaft opposite said arm externally of said base effective to con-

trol position of said arm, a counter balance adjusting screw threaded into said arm opposite said shaft, a contact strip disposed generally parallel to said arm and secured intermediate its ends to said arm, a cover member secured to said base having an arcuate groove on its inner face adjacent the path of oscillation of the outer end of said strip, an arcuate resistance element mounted in said groove, an edge of said element pressing against said outer end, a contact plate, a terminal passing through said cover member and securing said plate to the inner face of said cover member adjacent the path of oscillation of the inner end of said strip, and a pair of terminals passing thru said cover member at the respective ends of said element and attached to said element to secure the same in said groove.

6. A vane controlled adjustable resistor comprising a base, a shaft extending therethru, a vane mounted on one end of said shaft, an arm mounted on the other end of said shaft extending diametrically of said vane, a counter-balance screw threaded radially into the end of said arm remote from said shaft having a head disposed externally of said arm, a set screw mounted to secure said counter-balance screw, said arm having a threaded bore transversely thereof, a cross-balance screw threaded within said bore, and a set screw mounted to secure said cross-balance screw.

7. An adjustable resistor comprising a base, a wall mounted parallel to and spaced from a portion of said base so that a recess exists therebetween, a shaft rotatably mounted in said base and said wall and spanning said recess therebetween, a control arm secured to said shaft between said wall and said base and oscillatable thereby with respect to said base, a cover member secured to said base, a contact strip secured to said arm, an arcuate resistance element mounted to the inner face of said cover member adjacent the path of movement of one end of said strip, an edge of said element pressing against said one end, and electrical return means forming an electrical path between said contact strip and the exterior of said cover.
